(57) **CLAIM**

The ornamental design for a four petal teether, as shown and described.

DESCRIPTION

FIG. 1 is a front, perspective view of the four petal teether according to the present design;

FIG. 2 is a front elevation view of the four petal teether of FIG. 1;

FIG. 3 is a rear elevation view of the four petal teether of FIG. 1;

FIG. 4 is a right side view of the four petal teether of FIG. 1; FIG. 5 is a left side view of the four petal teether of FIG. 1; FIG. 6 is a top view of the four petal teether of FIG. 1; and, FIG. 7 is a bottom view of the four petal teether of FIG. 1.

The broken lines illustrate portions of the four petal teether which forms no part of the claimed design.
